HEAT EXCHANGERS

Richard M. Herbert, York, Pa., assignor to Borg-Warner Corporation, Chicago, Ill., a corporation of Illinois
Filed Mar. 17, 1958, Ser. No. 721,739
6 Claims. (Cl. 257—241)

This invention relates to heat-exchangers of the type adapted for transferring heat between a liquid heat-exchange medium, such as water, and an evaporating, or condensing, medium, such as a refrigerant.

The principal object of the invention is to provide a heat-exchanger of the type wherein the evaporating, or condensing, medium flows through the interior of a tube with the liquid heat-exchange medium flowing over the exterior of said tube in a transversely alternating path, thereby promoting efficient heat transfer between the two said mediums.

A further object of the invention is to provide a heat-exchanger of the type described, which is compact in form, of high efficiency, inexpensive and easy to fabricate, and having a low pressure drop therethrough. Yet another object of the invention is to provide for efficient heat transfer between an evaporating, or condensing, medium within a tube and a liquid heat-exchange medium flowing over the tube by causing the liquid heat-exchange medium to turbulently flow in an undulating path across said tube.

The invention consists of the novel constructions, arrangements and devices to be hereinafter described and claimed for carrying out the above-stated objects and such other objects as will appear from the following description of a preferred embodiment of the invention described with reference to the accompanying drawings, in which:

FIG. 1 is a vertical view of the hereindisclosed heat-exchanger with parts thereof in elevation and parts thereof in section to better show details;

FIG. 2 is a plan of the heat-exchanger with parts thereof broken away in order to better show details, and showing the refrigerant flow in an outwardly spiralling path;

FIG. 3 is a view similar to FIG. 2 but showing the refrigerant flow on its return inwardly spiralling path;

FIG. 4 is a vertical view of a flow directing baffle plate and an associated refrigerant tube before being formed into a spiral convolution;

FIG. 5 is a vertical sectional view, with parts thereof in elevation, taken on line 5—5 of FIG. 6; and

FIG. 6 is a detail showing the undulating flow path of the liquid heat-exchange medium over the refrigerant tube.

Like numerals refer to like parts throughout the several views.

Turning now to the drawings, and particularly FIGS. 1-3 thereof, there is shown a heat-exchanger comprising a casing 10, which casing includes a cylindrical side wall 11, a top wall 12, and a bottom wall 13. It will be apparent that the exact configuration of the casing is unimportant so long as there are at least two opposed walls in spaced apart parallel planes, such as top and bottom walls 12 and 13. A corrugated, spirally wound baffle plate 14, comprising a plurality of individual corrugations 14', extends between walls 12 and 13. A pair of gaskets 15 and 16 are provided between the baffle plate 14 and

2

walls 12 and 13 in order to provide a perfect seal therebetween.

The convolutions of baffle plate 14 are spaced apart to provide a spiral fluid passageway 17 between adjacent convolutions, the passageway 17 extending between top and bottom walls 12 and 13. An inspection of FIGS. 1 and 6 reveals that the flow through passageway 17 is normal to the corrugations 14'. The innermost convolution is so arranged as to define a chamber 18 within casing 10.

As shown, a plurality of spirally wound tube bundles 19 are provided in the passageway 17. Each tube bundle 19 comprises an outwardly spiralling tube pass 20 and an inwardly spiralling tube pass 21. It is apparent that the number of tube bundles provided varies with the application and size of the heat-exchanger. It is further apparent that each tube bundle could comprise but a single tube pass 20 or 21 rather than the double pass, as shown. The invention contemplates all such variations.

Baffle plate 14 is provided with a plurality of longitudinal rows of indentations 22, there being one row for each tube pass. An inspection of FIGS. 2, 5 and 6 shows that an indentation 22 is provided on the crest and trough of each corrugation 14' in baffle plate 14 traversed by a tube pass 20 or 21, the purpose of the indentations being to receive, properly space, and maintain in position the tube bundles 19.

Each tube bundle 19 has an inlet 23 and an outlet 24. A plurality of individual headers 25 are provided and 30 are connected to the individual inlets 23 by fittings 25'. Obviously a single header could be provided for feeding all inlets. A fluid container 26 is positioned within chamber 18 and is connected to the outlet 24 of the various tube bundles 19 by a plurality of lines 27 connected to respective outlets 24 by fittings 27'. Refrigerant exits container 26 by way of a line 28 provided for that purpose. A liquid heat-exchange medium inlet line 29 is provided leading into chamber 18. A liquid heat-exchange medium outlet line 30 leads through the cylindrical wall 11 of casing 10.

The inward terminal edge 31 of baffle plate 14 defines an inlet 32 to the passageway 17 formed by spirally wound baffle plate 14. The outward terminal edge 33 of baffle plate 14 defines an outlet 34 for passageway 17.

The distance between the various tube convolutions may be varied as desired either by varying the depth of the indentations 22, or by varying the size of the individual corrugation 14' in baffle plate 14. It is apparent that both the heat transfer rate and the pressure drop varies according to the spacing between the individual convolutions of the tube bundles 19. Further, the passageway 17 may be widened or narrowed according to how tightly the baffle plate 14 is wound, which also varies the heat-transfer rate and pressure drop.

In use, the heat-exchanger can function either as a refrigerant evaporator, or as a refrigerant condenser. The only difference would be in the functioning of container 26. When the heat-exchanger is to be used as a refrigerant evaporator, container 26 then functions as a refrigerant accumulator in order to prevent the passage of any unvaporized refrigerant from the heat-exchanger.

When the heat-exchanger is in use as a refrigerant condenser, then container 26 functions as a refrigerant receiver with the added advantage of being located in heat-exchange relation with the heat-exchange medium in

chamber 18, thereby providing additional heat-exchange surface.

In operation, the refrigerant flows into the various tube bundles 19 through headers 25 and thence flows in an outwardly spiralling path through tube passes 20 and, at the outermost point, reverses direction and flows on an inwardly spiralling path through tube passes 21, discharging into container 26 from whence it exists by way of discharge line 28. As was pointed out above, whether a single pass be used, or a multiple pass be used, is purely a matter of expediency, and both are contemplated.

The heat-exchange medium to be heated or cooled, dependent on the function of the heat-exchanger, flows into chamber 18 by way of inlet line 29. From chamber 18 the heat-exchange medium flows into the inlet 32 to passageway 17. The heat-exchange medium flows in an undulating path across tube bundles 19, as can clearly be seen in FIG. 6, this being the effect of the corrugations 14' in baffle plate 14. The continual back and forth passage of the heat-exchange medium across tube bundles 19 provides for highly efficient heat-exchange between refrigerant and the heat-exchange medium.

It will be noted that the liquid heat-exchange medium makes a single, spirally directed pass through the heat-exchanger before exiting through outlet line 30. It would make no difference to the functioning of the heat-exchanger if the direction of flow of the liquid heat-exchange medium were reversed with line 30 then functioning as an inlet and line 29 then functioning as an outlet.

While the primary purpose of baffle plate 14 is to cause the heat-exchange medium flowing through passageway 17 to undulate in its path across tube bundles 19, thereby promoting better heat-exchange, ancillary thereto is a heat-exchanging function of the baffle. An inspection of FIG. 5 clearly reveals that there is a direct exchange of heat between the various tube passes 20 and 21 and baffle plate 14 at the points of contact therebetween (indentations 22).

Dependent on the use of the heat-exchanger as an evaporator or condenser, heat flows from the liquid heat-exchange medium to the baffle plate 14 and thence to the various tube passes 20 and 21; or, reversely, from the various tube passes 20 and 21 to the baffle plate 14 and thence to the liquid heat-exchange medium.

It will be readily obvious that where it is not desired that baffle plate 14 perform a heat-exchanging function, the same may then be fashioned from a plastic material, in which case its only function would be that of causing the heat-exchange medium to flow in an undulatory path. In forming the baffle plate 14 of a plastic material, it is evident that gaskets 15 may be dispensed with and the plastic baffle plate 14 be affixed directly to walls 12 and 13 to provide a fluid tight seal therebetween.

Further, while I have set out the heat-exchanger as a unitary structure, it is apparent that wall 11 might be dispensed with and top and bottom walls 12 and 13 then function merely as sealing plates, providing a self-contained core. In such an instance, the self-contained core could be installed in an open tank in any multiple desired providing, in effect, an open circuit system. The invention contemplates all such modifications.

I wish it to be understood that my invention is not to be limited to the specific constructions and arrangements shown and described, except only insofar as the claims may be so limited, as it will be apparent to those skilled in the art that changes may be made without departing from the principles of the invention.

I claim:

1. A heat-exchanger comprising, a pair of opposed walls in spaced parallel planes; a corrugated, spirally wound baffle plate extending between and enclosed by said walls, the corrugations being normal to the plane of said walls, the convolutions of said baffle plate being spaced apart to provide a spiral fluid passageway be-

tween the convolutions normal to said corrugations and having an inlet and an outlet; and a tube bundle having an inlet and an outlet, said tube bundle being spirally wound in said fluid passageway in a plane normal to said corrugations forming a second fluid passageway.

5 2. The heat-exchanger of claim 1, and a chamber defined by the innermost convolution of said baffle plate and said opposed walls, and a fluid container in said chamber connected in a fluid flow path with said tube bundle.

10 3. A heat-exchanger comprising, a housing including, opposed walls in spaced parallel planes; a corrugated, spirally wound baffle plate extending between and enclosed by said walls, the corrugations being normal to the plane of said walls, the convolutions of said baffle plate being spaced apart to provide a spiral fluid passageway between the convolutions normal to said corrugations and having an inlet and an outlet; and a tube bundle spirally wound in said fluid passageway in a plane normal to said corrugations forming a second fluid passageway and having an inlet and an outlet, the convolutions of said tube bundle bearing on opposite sides thereof on the adjacent crests and troughs of said corrugated baffle plate.

15 25 4. A heat-exchanger comprising, a housing including, opposed walls in spaced parallel planes; a corrugated, spirally wound baffle plate extending between and enclosed by said walls, the corrugations being normal to the plane of said walls, the convolutions of said baffle plate being spaced apart to provide a spiral fluid passageway between the convolutions normal to said corrugations and having an inlet and an outlet, the innermost convolutions defining a chamber within said housing in fluid communication with said fluid passageway inlet; a tube bundle spirally wound in said fluid passageway in a plane normal to said corrugations forming a second fluid passageway and having an inlet and an outlet, the convolutions of said tube bundle bearing on opposite sides thereof on the adjacent crests and troughs of said corrugated baffle plate; and a fluid container in said chamber, the outlet of said tube bundle discharging within said container.

20 30 35 5. A heat-exchanger comprising, a pair of opposed walls in spaced parallel planes; a corrugated, spirally wound baffle plate extending between and enclosed by said walls, the convolutions of said baffle plate being spaced apart to provide a spiral fluid passageway between the convolutions normal to said corrugations and having an inlet and an outlet; and a tube bundle having an inlet and an outlet, said tube bundle being spirally wound in said fluid passageway in a plane normal to said corrugations forming a second fluid passageway, the convolutions of said tube bundle bearing on opposite sides thereof on said corrugated baffle plate, whereby a heat-exchange medium flowing through said spiral fluid passageway flows over the exterior of said tube bundle in a transversely alternating path.

25 30 35 40 45 50 55 60 65 70 75 80 85 90 95 6. A heat-exchanger comprising, a housing including, opposed walls in spaced parallel planes; a corrugated, spirally wound baffle plate extending between and enclosed by said walls, the corrugations being normal to the plane of said walls, the convolutions of said baffle plate being spaced apart to provide a spiral fluid passageway between the convolutions normal to said corrugations and having an inlet and an outlet, the innermost convolution defining a chamber within said housing in fluid communication with said fluid passageway inlet; a tube bundle spirally wound in said fluid passageway in a plane normal to said corrugations forming a second fluid passageway and having an inlet and an outlet, a fluid container in said chamber communicating with said tube bundle; said tube bundle and said spiral fluid passageway defining flow paths for first and second heat-exchange fluids respectively, said corrugations con-

fining said second heat-exchange fluid to an undulating path across the convolutions of said tube bundle.
